MACHINE FOR STRETCHING DISTENSIBLE SLEEVES

John W. Taylor, St. Joseph, Mo., assignor to
 Whitaker Cable Corporation, North Kansas
 City, Mo., a corporation of Delaware

Application January 28, 1949, Serial No. 73,278

2 Claims. (Cl. 29—235)

1

This invention relates to a machine capable of facilitating the placement of a relatively short, elastic, tubular, insulating member upon the terminal end of an electrical conductor, the primary aim being to provide means to distend the tubular insulator to an extent permitting the insertion of the terminal itself through the distended tube, whereby upon release of the tube it takes a position fitting tightly and neatly about the conductor at the point of joinder with the terminal.

It is common knowledge that electrical conductors of the kind used, for instance, in automotive wiring harnesses for the horn, lights, ignition circuits and the like are provided with metallic terminals that are soldered directly to the conductor after a portion of the insulation has been removed therefrom, the terminal often-times taking the form of a washer-like member having a diameter appreciably greater than the diameter of the conductor.

These conductor-terminal assemblies are provided with a short, tubular insulating member that covers the connecting area between the conductor and the terminal. Such tubular insulators are usually formed from rubber or other elastic material, and one of the most difficult problems in this field is the application of the tubular insulator as the last step of the operation.

It is the most important object of this invention, therefore, to provide a machine capable of automatically distending the tubular insulator above mentioned, whereby to permit the mounting thereof in place upon the conductor in a rapid, efficient and simple manner.

Another important object of the present invention is to provide a machine for distending tubular members having a rotatable drum provided with a plurality of outwardly-extending radial fingers arranged in symmetrical pairs, the fingers of each pair being movable toward and from each other and capable of threadably receiving the tube to be distended when the fingers are together, all to the end that, as the fingers are spread apart upon rotation of the drum, the tube will be stretched to a distended condition.

Another object of the present invention is to provide a machine as above set forth wherein there is provided within the rotatable drum stationary means engageable with one of the fingers of each pair and as the drum rotates to move said one finger outwardly whereby to stretch the tube on the fingers.

A further object of the present invention is

2

to provide a machine as above set forth wherein the rotatable drum is actuated in step-by-step fashion, to the end that the tube can be inserted upon one pair of fingers at one side of the drum and removed at the opposite side of the drum after the same has been mounted upon the conductor, the actuating means for the fingers being operable to return the fingers to a juxtaposed position as the drum continues its rotation.

10 A still further object of the present invention is to provide a machine having structure as a part thereof and operable automatically thereby for feeding a length of the tubular stock to the machine and to automatically cut such length of stock into short pieces, the cut tubes thereupon being automatically fed onto the foresaid fingers as the drum moves step-by-step.

Other important objects of the present invention relate to details of construction capable of 20 performing the main objects above set forth, all of which will be made clear or become apparent as the following specification progresses, reference being had to the accompanying drawings, wherein:

25 Fig. 1 is a top plan view of a sleeve-producing and applying machine for automotive ignition wires made in accordance with the present invention, parts being broken away to reveal details of construction.

Fig. 2 is a side elevational view thereof, parts 30 being broken away and in section for clearness.

Fig. 3 is an end elevational view thereof.

Fig. 4 is a fragmentary, detailed, elevational view showing a portion of that end of the machine opposite to that shown in Fig. 3, parts 35 being broken away to reveal details of construction.

Fig. 5 is a fragmentary, cross sectional view taken on line V—V of Fig. 3.

Fig. 6 is a longitudinal, vertical, cross sectional view taken on irregular line VI—VI of Fig. 1, looking in the direction of the arrows.

Fig. 7 is a detailed, fragmentary, cross sectional view taken on line VII—VII of Fig. 1, looking in the direction of the arrows.

Fig. 8 is a fragmentary, transverse, cross sectional view taken on line VIII—VIII of Fig. 6; and,

Fig. 9 is a detailed, cross sectional view taken on line IX—IX of Fig. 1.

The length of tubular stock of elastic material to be handled by the machine about to be described is illustrated in Figs. 1, 2 and 6 and designated by the numeral 10. The particular com- 50 position of tube 10 is of little importance to the

present invention other than the fact that the same is usually made from rubber substance or other elastic material capable of being cut into relatively short lengths and adapted for mounting upon a conductor adjacent the terminal end thereof as hereinabove set forth.

The machine, per se, includes a polygonal, flat base 12 adapted for fastening upon a table or bench as desired by the operator, said base 12 being cut away at one end thereof as at 14. A 10 pair of substantially identical, spaced-apart walls or frame members 16 and 18 extend upwardly from the base 12 adjacent one end thereof and are affixed to base 12 in any suitable manner, such as by machine bolts.

Openings (not shown) adjacent the uppermost end of the frame members 16 and 18 journal a transverse shaft 20. A hollow drum broadly designated by the numeral 22 is mounted upon the shaft 20, said drum being cup-shaped and provided with a closed end wall 24. Wall 24 is centrally perforated to clear the shaft 20 and has rigidly secured to the outermost face thereof a ratchet wheel 26 of appreciably smaller diameter than the diameter of drum 22, as indicated in Fig. 5.

Ratchet wheel 26 is provided with a key 28 for securing the same directly to the shaft 20, to the end that ratchet wheel 26 and drum 22 rotate as a unit with the shaft 20. Drum 22 has a cylindrical, innermost surface 30 and a polygonal, outermost face 32.

A plurality of radial fingers extend outwardly from the face 32 of drum 22, said fingers being arranged in pairs, there being four such pairs illustrated in the drawings and clearly indicated in Figs. 5 and 6. One of the fingers of each pair is designated by the numeral 34 and is stationarily secured to the drum 22 by means of a block 36.

Drum 22 is provided with a T-shaped, transverse slot 38 for receiving the block 36 having the same cross sectional contour, blocks 36 all being rigidly but removably secured to the drum 22 by means of screws 40 (Fig. 3). Stationary finger 34 is mounted directly upon the outermost face of the block 36.

Each pair of fingers is, also, provided with a movable finger 42 that is mounted in a slidable bar 44. An end view of bar 44 is illustrated in Fig. 6 to show the contour thereof, and the longitudinal, opposed ears 46 are provided as guides for bar 44 as the same reciprocates within the drum 22. Transverse openings 48 formed through the drum 22 in direct alignment with the slots 38 have a cross sectional contour complementary with the cross section of bar 44.

Each bar 44 has a block 50 secured directly to the innermost face thereof and disposed within the drum 22. Thus, blocks 50 are reciprocable with the bars 44 toward and away from the closed end 24 of drum 22. Each block 50 has a slot 52 formed in the end thereof proximal to the wall 24 of drum 22 for receiving a roller 54 journalled on a short shaft 56.

The open ends of the openings 48 opposite to blocks 36 are closed by plates 58 removably secured to the drum 22, said plates 58 each having a pin 60 extending into the openings 48. Pins 60 receive a spring 62 interposed between the plate 58 and the proximal end of bar 44 for holding the latter biased toward the corresponding block 36.

Thus, the two fingers 34 and 42 of each pair thereof are normally held together by the spring 62. When these fingers are together, they combine to present an elongated rod that is substan-

tially circular in cross section and having a diameter slightly less than the inside diameter of the tubular stock 10. Each finger 34 and 42 is, accordingly, substantially semi-circular in cross section, as indicated in Fig. 1.

A centrally-perforated, disc-like cam member 64 having an outside diameter slightly less than the inside diameter of drum 22 is mounted within the latter directly upon the shaft 20, as indicated in Fig. 6. Cam member 64 is provided with a peripheral flange 66 that extends substantially 180° therearound, flange 66 commencing at the ends thereof in a feather edge and progressively increasing in thickness, as illustrated in Fig. 1, from both ends thereof to its center. The inclined side of flange 66 faces the rollers 54, as indicated in Fig. 6.

The cam member 64 is loosely mounted upon the shaft 20 for free movement longitudinally therealong and is adjustable toward and away from the rollers 54 and, accordingly, away from and toward the innermost face of wall 24, through the medium of an L-shaped member 68. Member 68 extends into the open end of the drum 22 and is secured directly to a sleeve 70 freely circumcribing the shaft 20 between cam 64 and frame member 18.

Bolts 72 serve to removably secure member 68 and sleeve 70. One leg of the member 68 overlaps the outermost face of frame member 18 and is provided with an adjusting screw 74 that bears against the frame member 18 and is provided with a lock nut 76. A plurality of bolts 78 interconnect the sleeve 70 and the cam member 64 and, accordingly, as adjusting screw 74 is moved to increase the distance between the overlapping leg of member 68 and the frame member 18, cam member 64 will be moved toward the rollers 54.

Since the member 68 lies flatly against one vertical edge of the frame members 18, it serves also to prevent rotation of cam member 64 and sleeve 70 as drum 22 is rotated thereabout.

Rotation of the drum 22, together with the fingers 34 and 42 secured thereto, as well as the blocks 50 and their rollers 54, around the sleeve 70, cam member 64 and member 68 is accomplished by a swinging movement imparted to an arm 80, as indicated by arrows in Fig. 2. The means for swinging the arm 80 through its path of travel forms no part of this invention and has not been shown but may constitute such instrumentalities as an air cylinder, electric motor and crank arm or other prime mover.

The arm 80 is secured directly to a disc 82 by means of a plurality of bolts or the like 84. Disc 82 is centrally perforated and freely mounted upon the shaft 20 in close proximity to the ratchet wheel 26 on the outermost face of wall 24. Disc 82 is provided with an outwardly-extending ear 86 at its periphery that engages a roller 88 on one end of an arm 90 that is pivotally secured as at 92 on the innermost face of frame member 16, when arm 80 is swung downwardly to the lowermost end of its path of travel.

The arm 80 is secured to the innermost face of disc 82 in direct alignment with the ratchet wheel 26 and has a cavity 94 at its innermost end. A pin 96 freely slidable within the cavity 94 is held biased against the periphery of ratchet wheel 26 by a spring 98 within arm 80.

Thus, as arm 80 swings downwardly, pin 96 will engage one of the teeth of ratchet wheel 26 and cause rotation thereof, together with shaft 20 and drum 22. As arm 80 returns to the uppermost end of its path of travel, spring

93 will permit pin 96 to yield and clear the teeth of ratchet 26.

Step-by-step rotative movement of the drum 22 is, of course, defined by arm 80, but to further assure such movement, there is provided a plate 100 secured directly to the shaft 20 for rotation therewith exteriorly of the upright frame member 16. The plate 100 is provided with a flat portion 102 that corresponds respectively with each of the pair of fingers 34 and 42.

As drum 22 is rotated, these flats 102 align consecutively with and engage a vertically-reciprocable plunger 104 mounted within a case 106 that is, in turn, secured directly to the outermost face of the upright frame member 16. The case 106 is open at its uppermost end, and the plunger 104 is held biased upwardly against the periphery of the disc 82 by springs 108 within the case 106 and interposed between plunger 104 and the bottom wall of case 106.

Feeding means for the tubular stock 10 includes a pair of opposed rollers 110 and 112 secured directly to shafts 114 and 116, respectively. Shafts 114 and 116 are mounted in parallel relationship in a bifurcated carrier 118 that is, in turn, slidably mounted for vertical reciprocation upon an L-shaped support 120. Support 120 is secured directly to the uppermost face of the base 12 near one end thereof opposite to the frame members 16 and 18, and the upstanding leg thereof is rectangular in cross section as illustrated in Fig. 8.

Carrier 118 is provided with an elongated opening 122 for slidably receiving the support 120. The lowermost limit of travel of the carrier 118 is defined by a set screw 124 in support 120; and, through use of a lock nut 126, the extent of movement of carrier 118 toward base 12 is adjustably selected. Carrier 118 is provided with a pair of perforated guides 128 and 130 on opposite sides of the rollers 110 and 112 to direct the length of tube 10 between such rollers, as indicated in Fig. 6.

The openings in guides 128 and 130 are normally in alignment with aligned openings 132 and 134 formed in a pair of blocks 136 and 138, respectively. Block 138 is secured directly to the uppermost end of the support 120 through the medium of bolts 140, and the block 136 is interposed between the rollers 110 and 112 and the block 138 and is secured directly to the carrier 118 by bolts 142.

Block 136 is disposed in sliding contact with the proximal face of block 138 as carrier 118 is reciprocated vertically. It is clear that, as blocks 136 and 138 are thus shifted relatively, the openings 132 and 134 therethrough will be moved out of alignment and the tube 10 extending through the openings 132 and 134 will be sheared off between the proximal faces of blocks 136 and 138.

A pair of intermeshing gears 144 and 146 are secured to one end of shafts 114 and 116, respectively. Rotation of the shaft 114, and consequently roller 110 and gear 144 to in turn rotate roller 112 through gear 146 and shaft 116, is accomplished through an overrunning clutch 148 of the type illustrated in Fig. 9 of the drawings.

Clutch 148 includes a cylindrical housing 150, a ratchet member 152 within the housing 150 and secured directly to shaft 114 and a plurality of rollers 154 interposed between ratchet 152 and the innermost face of housing 150. It is clear that, as housing 150 is rotated in the di-

rection of the arrow as shown in Fig. 9, rollers 154 will wedge tightly against the ratchet wheel 152 and cause rotation of shaft 114.

When housing 150 is returned in the direction 5 opposite to the arrow in Fig. 9, rollers 154 will release automatically, and shaft 114 will not be caused to rotate in a counterclockwise direction. A plate 153 secured to that end of the housing 150 opposite to gear 144 and next adjacent the clutch 10 148 contacts a stop 155 on carrier 118 to limit the extent of rotative movement of housing 150 in said counterclockwise direction.

Housing 150 is provided with an ear 156 that pivotally receives through the medium of a pin 158 one end of a rod 160. A second rod 162 is pivotally secured as at 164 directly to the disc 82 on shaft 20. A longitudinal bore 166 adjustably receives a pin 168 that is held in place by set screw 170. Pin 168 extends into a bore that 20 is enlarged as at 172 and formed in the rod 162. An outwardly-extending shoulder 174 on the innermost end of the pin 168 limits the extent of sliding movement of pin 168 within bore 172.

That end of the arm 80 opposite to roller 88 25 is pivotally secured to the carrier 118 below block 136 through the medium of a pin 176. Upward reciprocable movement of the carrier 118 is defined by structure illustrated in Fig. 7 of the drawing and includes a Z-shaped, upstanding, 30 supporting member 178 mounted upon the uppermost face of the base 12. As illustrated in Fig. 7, the uppermost lateral leg of the member 178 overlaps a portion of the carrier 118 and carries a vertical, tubular housing 180.

35 A spring-loaded plunger 182 in housing 180 extends through the member 178 within the path of travel of carrier 118 and serves as a bumper as carrier 118 moves toward the uppermost end of its path of travel. Rotative movement of the disc 82 in one direction to limit the upward swinging movement of arm 80 is limited by a stop 184 shown in Figs. 1 and 2 that projects laterally from one face of the disc 82 and contacts an inclined, uppermost edge 186 of the frame member 16.

45 Fig. 4 of the drawings illustrates, also, a friction brake to prevent overrunning of the gears 144 and 146. This brake constitutes a plug 188 mounted within the gear 146 having a spring-loaded plunger 190 mounted therein and disposed to slidably engage the proximal face of carrier 118 as the gear 146 rotates.

Assuming the parts of the machine just described to be formed and assembled as set forth, 55 the operation is as follows:

As the arm 80 is swung downwardly from the position illustrated in Fig. 2 as indicated by the arrows in said figure, pin 96 engages ratchet 26 to rotate shaft 20. Disc 82 being secured directly to arm 80 rotates to move lug 86 against roller 88 and to cause swinging movement of the arm 90 on pivot 92.

Such movement of arm 90 raises the carrier 118 from the position resting upon set screw 124. 65 Such upward movement of the carrier 118 shifts the block 136 to shear off a short length of the tubular member 10. As the drum 22 is rotated because of rotation of shaft 20, the pairs of fingers 34 and 42 will move 90°. Such 90° step of rotative movement of drum 22 is defined by the disc 100 and one of its flat, peripheral portions 102 engaging the vertically-reciprocable plunger 104.

As the disc 82 is rotated approximately 90° 70 through the swinging movement of arm 80, arm

162 will be pulled away from arm 160 at the beginning of rotative movement of disc 82 because of the sliding interconnection between pin 168 and rod 162. As disc 82 is continued to be rotated to the end of its path of travel, shoulder 174 will engage the outermost end of enlarged cavity 172, and a longitudinal pulling movement will be imparted to the rod 160.

Such movement of rod 160 actuates clutch 148 to a set position for rotating the shaft 114 having roller 110 thereon when disc 82 returns to its starting position. Thus, as rod 80 returns to the uppermost end of its path of travel, rod 162 will move into abutting relationship with the proximal end of rod 160 to actuate the clutch 148.

Such operation of clutch 148 takes place only after the openings 132 and 134 of shearing blocks 136 and 138 have returned to the normal, aligned position. Obviously, such aligning takes place upon downward movement of carrier 116 through its inherent weight as lug 86 moves away from roller 88 and permits swinging movement of arm 90 back to the normal, inoperative position.

As clutch 148 rotates, the rollers 110 and 112, the stock of tubular material 10 will be fed longitudinally through the openings 132 and 134 and will force the short piece of severed tube within the opening 134 outwardly and onto the pair of fingers 34 and 42 that have been moved into alignment with the opening 134.

The fingers 34 and 42 commence spreading apart almost immediately from the time they move from the position in alignment with opening 134 to a position diametrically opposite thereto. Thus, when the short piece of tube on fingers 34 and 42 reaches the position illustrated in Fig. 1 opposite to the shearing assembly, including blocks 136 and 138, such short tube is fully distended; and an operator can easily and quickly insert the terminal and conductor that is to be furnished with insulating tube by projecting the same between the spread-apart fingers 34 and 42.

He thereupon grasps the short tube and pulls the same from the fingers 34 and 42. As these empty fingers move downwardly toward and between the frame members 16 and 18, the fingers 34 and 42 return to a position together for receiving another, undistended, short piece of tubular stock.

This action of the fingers 34 and 42 is accomplished by the rollers 54 riding upon the flange portion 66 of the cam member 64 which imparts a reciprocable movement to block 50 and, consequently, to bar 44 and the finger 42 thereon.

From the foregoing, it is clear that the entire operation of the machine from the time the material 10 is first fed thereto by the rollers 110 and 112 until the short, severed lengths thereof are removed from the fingers 34 and 42 to a position circumscribing a conductor and a portion of its terminal, is automatic and takes place through the movement of a single member, i. e., arm 80.

Having thus described my invention, what I claim as new and desire to secure by Letters Patent is:

1. In an insulating machine, a frame; a hollow rotatable drum having an open end; a plu-

rality of pairs of fingers mounted on the drum, one finger of each pair thereof being reciprocable along a path of travel parallel with the axis of rotation of the drum; roller means within the drum and attached to each reciprocable finger respectively; a non-rotatable cam within the drum and within the path of travel of the roller means; means for yieldably holding the rollers biased against the cam, said cam being reciprocable along said axis of rotation of the drum, said frame having an elongated shaft for rotatably mounting the drum, said cam being slidably carried by the shaft for reciprocation along the longitudinal axis thereof; a member connected with the cam for sliding the cam on the shaft, said member extending outwardly beyond the drum through said open end thereof; and structure for selectively holding the same in adjusted positions along its reciprocable path of travel, said structure including means movable on the member and engaging the frame exteriorly of the drum for holding the member against movement inwardly into the drum, said member bearing against the frame for holding the member and the cam against rotation with the shaft.

2. In a machine for facilitating the application of distensible tubes to conductor terminals, a frame having two upstanding spaced-apart walls; a rotatable shaft carried by said walls; a hollow drum having one closed end carried by said shaft for rotation therewith; a plurality of pairs of radially-extending fingers carried by said drum at spaced points on the exterior surface thereof, one finger of each pair being reciprocable along a path of travel parallel with the axis of rotation of said drum; roller means within said drum attached to each reciprocable finger respectively; a non-rotatable cam carried by said shaft within said drum, said roller means being engageable with said cam, whereby said reciprocable fingers are reciprocated as the drum rotates; and means for adjusting said cam along the axis of said shaft, said means comprising an L-shaped member having a first arm attached at one end thereof to said cam and extending beyond one of said spaced-apart walls, a second arm on said L-shaped member having a portion extending over the outside surface of said one wall, and an adjusting screw threaded through said second arm and bearing against said outside surface of said one wall, whereby adjustment of said screw causes said L-shaped member to be moved along a line parallel to said shaft, and said cam is thereby adjusted along the axis of said shaft.

JOHN W. TAYLOR.
